UNITED STATES PATENT OFFICE.

JOHN C. SMITH, OF PERRYSVILLE, OHIO.

ABRADING-TOOL.

SPECIFICATION forming part of Letters Patent No. 752,475, dated February 16, 1904.

Application filed September 8, 1903. Serial No. 172,310. (No model.)

To all whom it may concern:

Be it known that I, JOHN C. SMITH, a citizen of the United States, residing at Perrysville, in the county of Ashland and State of Ohio, have invented certain new and useful Improvements in Abrading-Tools; and I do declare the following to be a full, clear, and exact description of the invention, such as will enable others skilled in the art to which it appertains to make and use the same.

The invention has relation to an abrading-tool, a tool designed for use in connection with sand or emery paper for rubbing down and smoothing off work.

The object of the invention is to provide a tool of this character which shall be simple of construction, durable in use, and comparatively inexpensive of production and by the employment of which an uneven surface may be uniformly smoothed or rubbed over.

In the drawings, Figure 1 is a perspective view of my improved abrading-tool, one of the cranks being shown in its folded position and the other in its unfolded position ready for use. Fig. 2 is a longitudinal sectional view. Fig. 3 is a cross-sectional view.

In the drawings, 1 denotes the body of the tool, which has a flat base 2, provided with short bristle or brush tufts 2', forwardly and rearwardly projecting arms 3, and a handle or grip 4.

5 denotes rollers journaled in the arms and each having at one of its ends a ratchet-wheel 6.

7 denotes a strip of abrading material, which may be sandpaper or emery-paper. This paper is wound around one roller and has its opposite end connected to the other roller.

8 denotes cranks fixed to the ends of the rollers and by means of which the rollers are turned to bring the fresh or unused piece of abrading material under the brush-tufts of the body portion of the tool.

9 denotes pawls which are adapted to engage the ratchet-wheels and hold the rollers 45 in their adjusted positions. The cranks are preferably of the hinge type and when they are not in use are adapted to be folded down into the position shown in Fig. 1, where they are out of the way and will not interfere with 50 the work.

It is evident that a tool of this character will save much labor.

By providing the abrading-strip with a yielding backing, such as is furnished by the 55 tufts 2', irregular or uneven surfaces may be as easily smoothed down as smooth surfaces, as the tufts tend to force the abrading-strip into the hollows of the material being worked upon and will yield to any projections in the 60 work and permit the abrading material to slide over the same. In other words, the tufts act as an equalizing medium.

It will of course be understood that various changes in the form, proportion, and the minor details of construction may be resorted to without departing from the spirit or sacrificing any of the advantages of this invention.

Having thus described my invention, what I claim as new, and desire to secure by Letters 70 Patent, is—

An abrading hand-tool comprising a base having a handle on its upper sides and longitudinally-projecting arms at its ends, rollers revolutely mounted in said arms, means to rotate and means to lock the rollers, and a sheet of abrading material extended under the base from end to end thereof and having its end portions reversely wound on the rollers. 75

In testimony whereof I have hereunto set 80 my hand in presence of two subscribing witnesses.

JOHN C. SMITH.
